United States Patent Office.

CHARLES H. VANHOUTEN AND JOSEPH M. CRANE, OF NEWARK, NEW JERSEY.

Letters Patent No. 63,674, dated April 9, 1867.

IMPROVEMENT IN MACHINES FOR POUNCING HATS.

The Schedule referred to in these Letters Patent and making part of the same.

TO ALL WHOM IT MAY CONCERN:

Be it known that we, CHARLES H. VANHOUTEN and JOSEPH M. CRANE, of Newark, in the county of Essex, and State of New Jersey, have invented a new and improved Machine for Pouncing Hats; and we do hereby declare that the following is a full, clear, and exact description thereof, which will enable others skilled in the art to make and use the same, reference being had to the accompanying drawings, forming part of this specification.

The nature of our invention consists in the employment of a metal ring for the purpose of holding down the hat in its proper position upon the block while it is being pounced. It is hinged to one side of a conical disk that is adjusted up or down so as to fit the size or depth of the crown of the hat. It further consists of a treadle or shifting lever, in combination with a spiral spring and belts, which are employed to drive or rotate the hat. Various devices and methods have been employed for pouncing hats, but as yet all have proved unsuccessful, and of little or no utility, for the reason the work could not be done uniformly, as some portions of the hat would be nearly cut through and seriously damaged by the operation. It has therefore for a long time been the great desideratum of hatters and inventors to overcome and obviate this difficulty. By our invention we have successfully overcome the difficulty so long encountered, so that hats can be pounced in the most rapid and perfect manner.

To enable others skilled in the art to make and use our invention, we will proceed to describe its construction and operation.

Figure 1 is a longitudinal vertical sectional elevation of our improved machine for pouncing hats.

Figure 2 is an end elevation, with a section removed for the purpose of showing the construction of the machine.

Similar letters of reference indicate like parts in each of the figures.

A represents the frame, that may be made of either wood or metal, of suitable height and form, upon the top of which is secured the leaf or top B, that is rectangular in form. C represents a hat upon the conical block D; the said block D is secured to the vertical shaft E by means of a screw-thread made upon the upper end of said shaft, so that different sizes of blocks or forms may be used as desired for the construction or the forming of different kinds and sizes of hats. Over or around the block D is closely fitted an annular conical disk, F, that is allowed to move up and down on the block D, so as to correspond to the depth of the crown of the hat, where it is rigidly secured in its position by a flexible metal band, G. The respective ends of said band G are secured together and firmly gripe the annular conical disk F by means of the screw-bolt a. At the periphery of the disk F is secured, by means of a joint or hinge, an annular ring or binder, H, for the purpose of holding the hat in its position upon the block D while being pounced. The shaft E runs in suitable bearings, which are secured to the frame L. At the lower end of the said shaft E is secured the bevel gear-wheel I that fits and meshes into a corresponding bevel gear-wheel, J; the said wheel J is secured to the shaft K; the said shaft K is provided with journals which run in suitable bearings; the said bearings are also secured to the frame L; the said frame L, being firmly secured to the under side of the top or leaf B, supports and carries the shafts E and K. Upon the outer end of the shaft K are secured the tight and loose pulleys M and N, to which the power is applied to drive the machine. O is a rock-shaft, having journals at each end that have bearings which work in the frame A. At a convenient distance on the rock-shaft O is secured a treadle or shifting-lever, P, the upper end of which is bifurcated so as to admit the belt Q. At one end of the shifting-lever P is attached a spiral spring, R, the other end of which is attached to the top or leaf, the said spring operating that end of the lever. S is a crank, provided and fitted to the shaft K for the purpose of operating the machine by hand when desired.

The operation consists in first raising up the binders H (as shown in red lines) and placing the hat upon the block or former D, when the binder H is turned down, which fits just around the edge of the rim, where it is secured by means of the pin i; when the machine is put in motion by pressing down on the lever P, (which has its fulcrum on the rock-shaft O;) by this operation the belt Q is brought upon the face of the tight pulley, and the hat made to rotate, when the pouncing is manipulated by hand at leisure. By this means the operator is

enabled to have perfect control of the pouncing, and can judge of the extent and effect of the operation, so that he is not liable to injure the body of the hat by pouncing some parts thinner than others, which is the case when pounced by other methods. When the process of pouncing has been completed, by releasing the treadle or shifting-lever by the action of the spring upon the end of the said lever, the belt Q is thrown upon the loose pulley and the machine is stopped, when the pin i is removed, the binder is raised, the hat removed, and another placed upon the block for the same purpose.

Having thus described our invention, what we claim as new, and desire to secure by Letters Patent, is—

The sliding rim-block H, provided with the ring G, for adjusting the same, and having a hinged ring or button, H, in combination with the hat-block D, when arranged to operate substantially as herein shown and described, and for the purposes set forth.

CHAS. H. VANHOUTEN,
JOS. M. CRANE.
